UNITED STATES PATENT OFFICE.

HERMAN W. TOEPPER, OF DES PLAINES, ILLINOIS.

ANKLE-SUPPORT.

1,126,590.

Specification of Letters Patent.

Patented Jan. 26, 1915.

Application filed April 2, 1914. Serial No. 829,155.

To all whom it may concern:

Be it known that I, HERMAN W. TOEPPER, a citizen of the United States, residing at Des Plaines, in the county of Cook and

5 State of Illinois, have invented certain new and useful Improvements in Ankle-Supports; and I do hereby declare the following to be a full, clear, and exact description of the invention, such as will enable others 10 skilled in the art to which it appertains to make and use the same.

My invention relates to new and useful improvements in ankle supporters and has particular reference to a supporter adapted 15 to be secured to the heel of the shoe and engage the heel portion of the shoe externally thereof.

An important object of my invention is 20 to provide a supporter of the above mentioned character which is readily applicable to the heel of the shoe to provide the desired action and consists of novel means for securing the device in operative position.

A still further object of my invention is 25 to provide a device of the above mentioned character which will prevent the heel of the shoe from becoming worn on the side and will strengthen the ankle of the wearer of the shoe to which my device is applied.

30 An object of equal importance is to provide a device of the above mentioned character which is simple as to construction, reliable in its operation and cheap to manufacture.

35 The above and additional objects are accomplished by such means as are illustrated in the accompanying drawings, described in the following specification, and then more particularly pointed out in the claim which 40 is appended hereto and forms a part of this application.

With reference to the drawings, wherein I have illustrated the preferred embodiment 45 of my invention as it is reduced to practice, and throughout the several views of which, similar reference numerals designate corresponding parts: Figure 1 is a side elevation illustrating my device attached to the heel of the shoe, Fig. 2 is a detail perspective view of my device removed from the shoe, and Fig. 3 is a detail sectional view showing the hook.

Referring now to the drawing, the numeral 1 designates generally a plate forming the body portion of my device which is constructed of aluminum or other suitable

light metal and is concavo-convex to facilitate its engagement with the curved heel portion of the shoe designated A. The plate or body portion 1 is approximately 40 semi-elliptical in shape and is provided adjacent its upper terminal with segmental openings 2 and 3 which provide a skeleton frame work consisting of a center section 4 and side edges 5 and 6. It is therefore apparent that my device may be stamped out 45 of a single blank of metal and that in being of a skeleton nature it is lighter and not as noticeable as would be the case if it were formed of a solid piece of metal. A pair 50 of enlarged ear portions 7 and 8 are formed upon the lower terminal of the plate 1 and are each apertured as at 9 for the reception of screws 10 or other suitable fastening means which are adapted for engagement 55 with the heel 11 of the shoe.

As a means for clamping the plate in proper position upon the heel 11 this invention employs a pair of hook members 12 downwardly turned which are formed integral 60 with the plate or body portion 1 adjacent the lower terminals of the openings 2 and 3 therein and are adapted for engagement with the shoe A at a point between the heel and the heel portion of the shoe 65 as will be clearly seen with reference to Fig. 1. It will thus be seen that a skeleton frame work consisting of the sections 4, 5, and 6 are disposed above the upper portion of the heel 11 and engage the sides of the 70 heel section of the shoe A whereby the foot of the wearer of the shoe is supported in such a manner as to prevent the ankle from turning and consequently the heel is worn straight and not upon either side as is usually the case with persons having weak 75 ankles.

If desired the supporter may be decorated with suitable designs for the purpose of 80 ornamenting the shoe but it is not thought necessary to illustrate such decoration in this connection.

In reduction to practice, I have found 85 that the form of my invention, illustrated in the drawings and referred to in the above description, as the preferred embodiment is the most efficient and practical; yet realizing that the conditions concurrent with the adoption of my device will necessarily vary, I desire to emphasize the fact that various 90 minor changes in details of construction, proportion and arrangement of parts may 95

be resorted to, when required, without sacrificing any of the advantages of my invention, as defined in the appended claim.

What is claimed is:—

3 An ankle supporter consisting of a plate having segmental openings formed therein to provide a skeleton construction and having a V-shaped cut-out portion in its lower edge forming ears on opposite sides of the
10 plate, said ears to engage the heel of a shoe and having openings therein to receive fas-

tening means, and downwardly turned hooks formed integral with said plate at the lower ends of said segmental opening and arranged to engage in a shoe between the uppers and heels thereof. 15

In testimony whereof I affix my signature in presence of two witnesses.

HERMAN W. TOEPPER.

Witnesses:

O. A. JACOBS,
ALVIN KUHLMAN.
